UNITED STATES PATENT OFFICE.

CECIL A. JONES, OF NORTH ZULCH, TEXAS, ASSIGNOR OF ONE-HALF TO THEODORE M. SHANNON, OF NORTH ZULCH, TEXAS.

FOLDING CHICKEN-COOP.

1,199,079.

Specification of Letters Patent. Patented Sept. 26, 1916.

Application filed May 5, 1915. Serial No. 26,064.

To all whom it may concern:

Be it known that I, CECIL A. JONES, a citizen of the United States, residing at North Zulch, in the county of Madison and 5 State of Texas, have invented new and useful Improvements in Folding Chicken-Coops, of which the following is a specification.

The present invention relates to improvements in crates and has particular reference to poultry crates.

The invention contemplates the provision of a crate of this character wherein the side and end walls, together with the top may be 15 folded in compact form for shipment, combined with a novel construction of means for locking the parts in either folded or set up position.

In the drawing forming part of this application like numerals of reference indicate similar parts in the several views wherein:

Figure 1 is a perspective view of the crate ready for use. Fig. 2 is a longitudinal sectional view. Fig. 3 is a transverse sectional view. Fig. 4 is a perspective view with the crate folded. Fig. 5 is a detail fragmentary view of one corner of the cover showing the association of the locking means therewith. Fig. 6 is a similar view of one corner of the 30 cover at the opposite end thereof. Fig. 7 shows a modified form of the manner of securing the wire fabric to the side and end walls.

Referring more particularly to the drawing the crate consists essentially of a bottom 5, side walls 6, end walls 7 and a top 8. Of course the crate can be constructed of any suitable material, but as shown in this particular instance the bottom is preferably 40 constructed of wood, while the side and end walls are composed of the metallic frames 9 covered by wire fabric 10 of any suitable mesh. The frames are further strengthened by the vertically and diagonally disposed 45 braces 11 and 12 respectively.

The side walls 6 are hinged directly to the bottom by means of the strips 13 passed through openings in the lower edge of the frame at spaced intervals, the strips being 50 formed to provide loops 14, and terminally secured to the longitudinal edges of the bottom 5. Rising from the opposite end edges of the bottom 5 are vertical flanges 15 to which the end walls 7 are hingedly connected in any suitable manner. By reason

of this arrangement the side walls 6 are permitted to fold directly upon the bottom 5, after which the end walls 7 are folded inwardly above the said side walls. In this position of parts the cover 9 is then placed 60 over the side and end walls, the depending flange 16 of which embracing the edges of the bottom 5 and is of a depth equal to the combined height of the bottom with the side and end walls in folded position. In placing the cover in this position, the pins 17 projecting inwardly from one end of the flanged portion of the cover are arranged within suitable openings in the bottom 5, while the opposite end of the cover is fixedly 70 secured to the opposite end of the bottom by means of the pins 18 carried at the opposite ends of a flat spring 19, projecting through suitable openings in the flange 16 and into suitable openings in the opposite end of the 75 bottom 5. As will be readily apparent the pins 18 are effectively held within the openings in the bottom 5 under tension of the spring 19, thereby locking the cover in position upon the bottom and confining the side 80 and end walls in folded position between the cover and the bottom 5. As shown in Fig. 4 the crate can be folded in the manner hereinabove described so as to occupy a minimum amount of space when not in use for 85 shipping purposes or the like.

Now when it is desired to use the crate, the pins 18 are first disengaged from the openings in the bottom 5, after which this end of the cover can be slightly elevated, 90 and moved endwise to disengage the pins 17 from the openings at the opposite end of the bottom 5, thus permitting the cover to be wholly separated therefrom. The end walls 7 are then moved to vertical position, 95 and the side walls swung outwardly to engage the flanges 20 formed on the end walls 7, the latter supporting the side walls in set up position until the cover is placed in position thereon. In this position of parts the 100 pins 17 are passed through the openings 21 in one of the end walls 7, while the pins 18 project through similar openings 22 in the opposite end wall 7, when the cover is operatively positioned upon the crate. As 105 above stated the flanges 20 prevent outward swinging movement of the side walls 6 while the pins 17 and 18 are arranged inwardly of the side walls 6 and thus prevent inward swinging movement thereof when the parts 110

are in set up position. The pins 18 are effectively held in position within the openings in one of the end walls 7 under tension of the spring 19, and as will be apparent 5 with the cover in operative position both the side and end walls are effectively locked in upright position.

The cover 8 is provided with a central opening 23 to permit access to be had to the 10 crate when desired, this opening being controlled by means of a sliding door 24 guided in its movements by means of the channel-like bars 25 extending transversely of the cover and arranged at the opposite sides of 15 the opening. The cover is provided with a knob or handle 26 for operating the same.

While the wire fabric may be secured in any suitable manner to the metallic frames constituting the side and end walls of the 20 crate, it is preferred that these frames be punched at intervals as at 27 shown in the modified form in Fig. 7, and the material bent to provide hook-like portions 28 to which the wire fabric is adapted to be se- 25 cured.

It is to be noted that in the construction of my device a single locking means carried by the cover 8 is used in connection with the bottom 5 in the folded position of 30 parts, while the same locking means is adapted for operative association with the end walls 7 when the parts are arranged in set up position to prevent collapsing thereof.

It is believed that from the foregoing de- 35 scription the nature and advantages of the

invention will be readily apparent without requiring a more extended explanation and therefore the same has been omitted. However I desire to have it understood that I do not limit myself to the precise construction 40 herein shown and described, as the same is merely illustrative and that various changes may be made when desired as fall within the scope of the appended claim.

What is claimed is:—

45 A crate comprising a bottom, inwardly foldable side and end walls hinged to said bottom, corner flanges on said end walls and adapted to engage the side walls exteriorly thereof in set up position, a cover 50 having a depending flange adapted to embrace the upper edges of said walls, spring pressed pins normally projecting through openings in the flange of said cover, and adapted to project through similar openings 55 in said end walls with the cover in position, said pins being disposed inwardly of the side walls and functioning to hold the latter in set up position, said cover being adapted to be arranged on said side and 60 end walls in folded position, whereupon said pins project through openings in the bottom to hold said parts associated.

In testimony whereof I affix my signature in presence of two witnesses.

CECIL A. JONES.
